P. TRUSKOWSKI

COW TAIL HOLDER

Filed Feb. 11, 1924

FIG. 1.

FIG. 2.

FIG. 3.

By

J. K. Bryant
Attorney

UNITED STATES PATENT OFFICE.

PAUL TRUSKOWSKI, OF REMSEN, NEW YORK.

COW-TAIL HOLDER.

Application filed February 11, 1924. Serial No. 692,033.

To all whom it may concern:

Be it known that I, PAUL TRUSKOWSKI, a citizen of Poland, residing at Remsen, in the county of Oneida and State of New York, have invented certain new and useful Improvements in Cow-Tail Holders, of which the following is a specification.

This invention relates to new and useful improvements in cow tail holders.

10 An important object of the invention is to provide means for preventing cows from switching their tails during such times as they are being milked.

15 A further object of the invention is to provide means of the above mentioned type which is in the form of a resilient clamp that may be employed for securing a cow's tail to one of its hind legs.

20 A still further object of the invention is to provide means for restraining the tension of the resilient clamping means so that its engagement with the cow's leg will not result in injury to the latter.

25 Other objects and advantages of the invention will be apparent during the course of the following description.

30 In the accompanying drawing forming a part of this specification and in which like numerals are employed to designate like parts throughout the same,

35 Figure 1 illustrates a fragmentary side elevational view of a cow, illustrated in dotted lines, and the tail holding means embodying this invention operatively associated therewith,

40 Figure 2 is a longitudinal sectional view of the tail holding device embodying this invention, and

45 Figure 3 is a side elevational view of the tail holder illustrated in Figs. 1 and 2.

In the drawing, wherein for the purpose of illustration is shown the preferred embodiment of this invention, the numeral 5 designates the arcuate jaw members which are provided at their outer engaging ends with oppositely rolled edges 6, as best illustrated in Fig. 2. These arcuate jaw portions 5 are formed integrally with the handle portions 7 which are provided with side flanges 8 extending longitudinally of the edges of the same and terminating at their inner ends in ears 9 that are apertured for receiving the bolt and nut 10 for the pur-

pose of pivotally connecting the said handles and jaws.

55 Suitably coiled around the portion of the bolt 10 positioned between the opposite pivotally connected pairs of ears 9 is a resilient piece of wire 11 having its opposite ends 12 extending longitudinally inwardly of the opposed handles 7. It will be seen that this resilient wire will cause the handles to be moved away from each other and will thereby cause the curled edges 6 to be forced toward each other.

60 By inspecting Fig. 1, it will be seen that the cow's tail 13 may be secured to the upper portion of the leg 14 by positioning the said tail and a portion of the leg between the arcuate jaws 5. The curled end edges 6 of the jaws 5 will provide smooth surfaces for engaging the leg 14.

65 It will be seen that the outer ends of the jaws 5 will not be in engagement with each other when the same are positioned upon opposite sides of the leg 14. This spacing of the ends of the jaws 5 will cause the resilient wire 11 to be under considerable tension with a result that the said ends 6 will so tightly engage the cow's leg that 70 injury to the latter would be likely to result.

75 For this reason, an arcuate, resilient metal strap 15 is secured to the end of one of the handles 7 and is provided with teeth 16 adjacent its free end which are to be employed for engaging the flange 17 carried by the end edge of the opposite handle 7 for retaining the jaws 5 in fixed relation in 80 respect to each other. This holding of the jaws 5 will remove unnecessary pressure on the leg 14.

85 It is to be understood that the form of this invention herewith shown and described is to be taken as a preferred example of the same, and that various changes in the shape, size, and arrangement of parts may be resorted to without departing from the spirit of the invention or the scope of the subjoined claim.

90 Having thus described the invention, I 100 claim:—

95 In a device of the type described, a pair of cooperating arcuate clamping jaws, a handle portion carried by each jaw, means for pivotally connecting said handles in 105 proximity to said jaws, resilient means for

normally retaining the outer ends of said jaws in engagement with each other, and means carried by the inner ends of said handles for retaining said jaws in fixed relation to each other against the action of said resilient means, said last mentioned means including a transverse flange formed on the end edge of one handle and an

arcuate resilient metal strap carried by the end of the remaining handle and having a plurality of teeth formed on the free end thereof adapted to selectively engage said flange.

In testimony whereof I affix my signature.

PAUL TRUSKOWSKI,
